UNITED STATES PATENT OFFICE.

MATTHEW F. BAYER, OF KENOSHA, WISCONSIN, ASSIGNOR TO SIMMONS COMPANY,
OF KENOSHA, WISCONSIN, A CORPORATION OF DELAWARE.

EXTENSION COUCH.

1,418,055.

Specification of Letters Patent. Patented May 30, 1922.

Application filed December 19, 1919. Serial No. 346,087.

To all whom it may concern:

Be it known that I, MATTHEW F. BAYER, a citizen of the United States, residing at Kenosha, in the county of Kenosha and State 5 of Wisconsin, have invented certain new and useful Improvements in Extension Couches, of which the following is a specification.

My invention relates to improvements in extension couch, and although capable of numerous applications, has a specific application to that type of folding couch in which there are a pair of sections adapted to nest one upon the other thereby conserving space when the couch is not in use for sleeping 15 purposes.

The principal objects of the invention are to provide an improved extension couch so organized that the mechanism may be manipulated from one side only, or from either 20 end of the couch without danger of cramping the parts, thereby insuring smooth and positive action; to provide a sliding couch of the class described in which the mechanism can be operated with a minimum number of manipulations thereby rendering the device substantially automatic in its operation; to provide an improved construction which shall be simple and inexpensive to manufacture and economical in operation, and in general 25 to provide a neat and practical extension couch of the character referred to.

In the drawings which show my invention as applied to a sliding couch of the two-leaf type—

Fig. 1 is a plan view of a couch showing the arrangement of the parts when the couch is condensed or folded;

Fig. 2 is a front elevation of the couch illustrated in Fig. 1;

Fig. 3 is a section taken on line 3—3 of Fig. 1;

Fig. 4 is a view similar to Fig. 3 but showing the couch half way extended;

Fig. 5 is a view similar to Fig. 3 but showing the couch fully extended;

Fig. 6 is a section taken on the line 6—6 of Fig. 4;

Fig. 7 is a section taken on the line 7—7 of Fig. 5, and

Fig. 8 is a section taken on the line 8—8 of Fig. 7.

Referring to the drawings, it will be observed that the end frames 10 and 11 of the couch are of the continuous post type comprising posts 12 and 13 and top rail 14. The

fillers 15 are supported by a bottom rail 16 which also serves to some extent to tie together the lower leg extensions of the posts 12 and 13.

The end frames 10 and 11 constitute supports for the detachable main frame to which the stationary half of the bed spring is secured. The spring 17, which in this instance, is of the link fabric type, is connected to two series of end helicals 18, said 60 end helicals being engaged with a pair of oppositely disposed end cross pieces 19, which take the form of lengths of angle iron.

The rails or stretchers of said stationary frame part comprise a pair of angle irons 20 70 and 21, depressed below the level of the spring 17 for the purpose of permitting sag of the bed spring when occupied, and also in order to permit the movable frame section to slide in between the spring and the rails. 75

In order to furnish a connection between the cross angles 19 and the rails 20 and 21, the said cross angles 19 are united by means of rivets 22, or other approved means, to vertically extending angle iron members 23 80 and 24, the lower ends of which extend downwardly to connect with the upper ends of oblique braces 25 and 26, such connections being made by a plurality of rivets, or other suitable uniting means. The vertical angle 85 irons 23 and 24 are mated with corresponding similarly arranged angle iron members 23^a and 24^a spaced therefrom as shown best in Figure 8 and connected thereto by being secured to the cross angles 19 in the same 90 manner as the angle irons 23 and 24.

One of the said mated pairs of angle irons has its side flange extended and folded over as shown at 27 in order to close the upper end of the rectangular space located between 95 the pairs of angle irons. The said pairs of angle irons 23 and 23^a, and 24 and 24^a are tied together by means of stout transverse pins 28, by means of which the frame is detachably connected to the posts of the end 100 frames. Such connection comprises a duplex loop stamping 29, the loop of which is reduced in height and extends through an aperture in the side of the hollowed bed post 12. Said stamping 29 is rigidly secured in 105 position by means of a taper key or wedge 30 inserted in the loop, distortion of the relatively thin wall of the post 12, being prevented by an outer face plate 31 and an inner plate 32. 110

By reference to Figure 6 it will be observed that the stamping 29 is made with a notch 33 somewhat inclined so as to exert a wedging action on the connecting pin 28 and thus forcing the outer edges of the angle iron members 23 and 23^a, tightly into engagement with the face plate 31.

It will be readily observed that by reason of the construction above described, it is readily possible and convenient to detach the end frames of the bedstead from the spring supporting frames, thereby enabling different designs of end frames to be used in connection with the same uniform construction of spring, frames, and associated parts.

The fabric on the folding or extensible section of the couch is connected to a pair of cross angles 34, the outer ends of which are bent down as shown at 35 to constitute legs, which are fitted with suitable casters 36 to facilitate free sliding movement of the extension section. The inner ends of the cross angles 34 are maintained the correct distance apart by means of a longitudinally extending rail 37 of angle iron cross section, the ends of which are bent up obliquely as shown at 38 and united to the horizontal flanges of the angle iron 34 by rivets as indicated at 39. The legs 35 are maintained in proper spaced relation by means of an angle iron member 40, riveted to said legs, and braced by means of a pair of obliquely extending members 41.

The folding or extension section of the couch is arranged to slide under the stationary section and in order to reduce friction the inner ends of the cross pieces 34 of the extension section are equipped with rollers 42, journaled on pins 43 rigidly secured to the ends of the said cross pieces 34. Said rollers 42 operate on tracks formed by the inwardly projecting horizontal flanges of transversely extending angle irons 44 vertically beneath the cross angle irons 19. The said angle irons 44 are united to the vertically extending angle iron members 23 and 23^a and 24 and 24^a in substantially the same manner as the angle irons 19, but in reversed relation as shown clearly in Figs. 6 and 7.

In order to bring the two sections of fabric more nearly into the same horizontal position when the couch is extended, I prefer to mount a short raised track bar 45 at the outer ends of the track angles 44, so that, as shown best in Figs. 5 and 7, when the couch is extended, the roller will run up the incline 46 and elevate the inner end of the folding couch section into the position shown, wherein it will be seen by reference to Fig. 7 that the edges of the fabrics of the two sections are vertically separated by a distance barely equal to the diameter of the helical.

In order to assure a depression of the top

of the folding fabric section sufficiently to enable same to slide conveniently under the fixed section when the couch is being folded, a long oppositely disposed track bar 47 is mounted on the underside of the horizontal flange of the upper cross angles 19, to which the stationary fabric is connected. It will be obvious that the outer end 48 of said upper track bar 47 must stop short of the inner end of the short track bar 45 and be suitably inclined to enable the roller 42 to switch from its upper to its lower position at the commencement of the folding movement.

Novel means are employed to effect rapid, convenient, and what may be termed, automatic folding of the couch. Such means comprise a foot operative member, which by a single simple manipulation serves either to extend or fold the couch as the case may be. Such means comprise as one of its principal elements a torsion shaft 49 extending longitudinally of the couch within the angle of the rail 20, and mounted to rotate in suitable bearings formed in the lower ends of the vertical angles 23. On each end of said shaft is keyed a hub 50 from which extends an arm 51, said arm having its front end connected to the pin 43 by means of a leg 52. Means, for instance, a strong torsion spring 53 are employed preferably at each end of the torsion shaft 49 to cause said shaft 49 to rotate in a direction to lift the front end of the arm 51. Said spring surrounds the shaft 49 and has one of its ends hooked under the edge of the rail 20 as shown at 54, its other end being extended forwardly as shown at 55, and hooked under the lower edge of the arm 51 as shown at 56. In order to apply manipulating pressure conveniently to the arm 51, the latter is equipped with a pair of rods or bars 57 and 58, the upper ends of said bars 57 and 58 being spaced apart and united to the arm 51, while the lower ends are brought together and bent out horizontally as shown at 59 in order to afford a support for the foot of the operator.

In operating the automatic mechanism which is described, and assuming that it is desired to extend the couch from the position shown in Fig. 3 to the position shown in Fig. 5, the operator places a foot on the pedal 59 and presses down smartly. The effect is two-fold. First: It naturally causes the arm 51 to swing down into substantially the position shown in Fig. 4, thereby drawing the movable section of the couch forward by the links 52, in addition to which the tension of spring 55 is substantially increased, thereby causing the free end of the arm 51 to press upwardly with increased force when the foot is removed from the pedal.

In practice, the momentum acquired by

the movable section during the initial pedal operated half of its operative movements is 65 ample sufficient to carry it beyond the dead center position of the link 52 so that after 5 the foot has been removed, the bars 51 and 52 function as a toggle. In straightening out the toggle the spring 53 forces the movable section to complete its outward movement and come to rest in the position shown 10 in Fig. 5.

When the couch is fully extended, the arm 51 and the link 52 are in substantial alignment as shown in Fig. 5, excess upward movement of the arm 51 being prevented by 15 a soft rubber bumper 60 which engages the underside of the track angle 44. Hence, it will be seen that when the couch is folded, it is locked in such position and cannot be unlocked except by operation of the pedal.

20 It will be manifest in view of the above description of the operation, the same result, but in reverse direction, is secured if the pedal is pressed when the couch is extended. In that case, the first portion of the movement 25 will be under the influence of the foot-applied pressure and the inward movement will be completed by the spring. In either case, the foot should preferably be removed entirely from the pedal as soon as the latter 30 has reached its limit of downward movement, thereby enabling the spring to perform its duty unrestricted.

I claim as my invention:

1. In a folding couch, the combination of 35 a stationary mattress frame section, and a movable mattress frame section slidable with reference to the stationary section, a manually controlled arm mounted to swing on the stationary section, spring means opposing swinging movement of said arm, and means connecting the outer end of said arm to the movable section.

2. In a folding couch, the combination of 45 a plurality of sections for supporting the mattress, one of said sections being slidable relative to the other section, an arm pivotally mounted on the relatively stationary section, a spring always tending to rotate said arm in one direction only, and a link 50 operatively connecting the end of said arm to the slidable section, the arrangement being such that the spring will oppose initial folding or unfolding movement of the slid- 55 able section, but will assist in the completion of said movement.

3. In a folding couch, the combination of 60 a stationary frame provided with a mattress section, another mattress section horizontally slidable on said frame, and adapted when extended to form with the first stationary section, a mattress support of the desired width, a horizontal shaft arranged lengthwise and towards the rear of the stationary frame, and adapted to rotate there-

on, an arm rigid with said shaft, and extending forwardly below the plane of the stationary mattress section, a spring tending to elevate the forward end of said arm, a link connecting the forward end of said arm to the rear end of the sliding section, 70 and a means for effecting manual rotary movement of said shaft to depress the forward end of said arm.

4. In a folding couch, the combination of 75 a stationary frame section a movable frame section slidable relative to the other main frame section, manually operated means for effecting sliding movement of said sliding section into a substantially midway position of its movement, and automatic means for 80 completing said movement.

5. In a folding couch, the combination of 85 a stationary frame section a movable frame section adapted to slide with reference to the stationary section, a manually operated member for causing an initial movement of the sliding section in either direction, and automatic means for completing the full sliding movement of said sliding section.

6. In a folding couch, the combination of 90 a pair of sections, one movable with reference to the other, toggle members connected respectively to the two sections, manual means for operating said members for effecting an initial relative movement of said sections and a spring for completing said movement.

7. In a folding couch, the combination of 95 a stationary section a movable section, a manually controlled arm mounted to swing 100 on said stationary section to effect relative movements of said sections in either of two directions, a spring opposing the initial portion of the movement in either direction, and a link connecting the outer end of said arm to the movable section.

8. In a folding couch, the combination of 105 a stationary mattress frame section, and a movable mattress frame section arranged to slide and telescope with reference to the stationary section, an arm arranged to pivot on said stationary section on an axis ar- 110 ranged lengthwise of the stationary frame section, and at the rear thereof below the mattress surface, the arm extending forwardly, a spring tending constantly to elevate the front end of the arm, a link of substantially the same length as the arm, connecting the forward end of said arm to the rear of the sliding mattress section, and a 115 manually controlled member for depressing said arm against the action of said spring, said spring serving to oppose the initial portion of the folding or unfolding movements of the couch, but to assist in the completion 120 of the subsequent portion of each of said movements.

MATTHEW F. BAYER.
